UNITED STATES PATENT OFFICE

2,331,625

ELASTIC COLLAR HOLDER

Albert C. Patch, Topeka, Kans.

Application August 16, 1943, Serial No. 498,769

4 Claims. (Cl. 24—81)

This invention relates to garment accessory devices, with particular reference to clamps or holders for the points or meeting end portions of shirt collars, the function of which holding device is to maintain said points or meeting ends of the collar in the proper neat and snug relation to the necktie at the front of the shirt collar.

The invention therefore comprises an improved form of collar holding device having means for retaining engagement with the points or meeting ends of the collar, as well as a yielding or elastic connection adapted to enable the device to compensate for abnormal strains or pulls (incident to its wearing position) without releasing said engagement with the ends of the collar.

For accomplishing this purpose I provide practical and efficient collar engaging elements for maintaining a reliable and detachable connection with the ends of the collar, and also an elastic or resilient element having its opposite ends connected with said collar engaging elements, and enclosed by a suitable tubular sleeve or guard member.

One important feature of the present invention is the improved form of assembly of the parts whereby the collar engaging or gripping elements and their guard member for the connecting element are constructed to cooperate for not only providing limiting stops for the relative movement of the parts, but also for holding them against relative rotative movement—and in addition, to provide a simple means of attaching said gripping elements to the elastic or resilient element, and of such a character as to positively eliminate any possibility of those elements becoming disconnected.

The improved construction is furthermore of a simple and inexpensive type, adapted for economical manufacture, and also of a nature appropriate for receiving a neat and attractive finish, rendering it suitable for wearing purposes.

With the foregoing general objects in view, the invention will now be described by reference to the accompanying drawing showing one specific form of construction which has been found suitable for the practical embodiment of the proposed improvements, after which those features and combinations which are deemed to be both novel and patentable will be particularly set forth and claimed.

In the drawing—

Figure 1 is a front perspective view showing the improved collar holding device in appropriate wearing position, or in connected relation to the

points or meeting end portions of a shirt collar and beneath the tie at the front of the collar;

Figure 2 is a plan view of the improved device, on a somewhat larger scale;

Figure 3 is a rear edge view of the device;

Figure 4 is a longitudinal sectional view, representing a section taken on the line 4—4 of Figure 3; and

Figure 5 is a transverse section, taken on the line 5—5 of Figure 2.

The present invention is the nature of an improvement over the collar and tie clasp device illustrated in my Patent No. 2,195,468, dated April 2, 1940.

Referring now to the accompanying drawing in detail, the improved device is shown therein as comprising a pair of forked attachments or collar-gripping elements in the form of collar clips 5, each having a pair of fingers 7 and at least one of said fingers of each pair having sufficient spring or resilient action for facilitating the slipping of the clip over the edge of the shirt collar 10 and thereafter maintaining the clip in secure gripping engagement with said collar.

The collar clips or gripping elements 5 are connected to the opposite ends of a suitable elastic or yielding member, which may be of any desired type for this purpose, and which is herein illustrated as comprising a coil spring 14 of appropriate length, the ends of which may be attached in any suitable manner to said clip elements. In the present illustrated form of the improved construction I prefer to loop the ends of said spring 14 over finger projections 16 which are formed integral with the inner ends of the shank or stem portions 18 of said elements 5, as clearly illustrated in Figure 4.

The said coil connecting spring 14 as well as the shank or stem portions 18 of the clip elements 5 are enclosed in a tubular sleeve member 20 of appropriate length and which may conveniently be made of split construction rolled into cylindrical form, and also cut away along its split or seam line to form mating recesses or notches 22 which are so located as to cooperate to provide slots for accommodating the aforesaid finger projections 16. These slots are also designed to be of proper length to provide shoulders 24 at both ends of the slots for acting as stops to limit both the expanding and contracting movements of the spring 14. In addition it is also obvious that after the ends of said spring 14 are assembled in attached relation to said finger projections 16, the extension of said fingers out through the slots formed by said recesses 22 will effectually

prevent any disengagement of the ends of the spring from the fingers 16 of the clips 5.

The use of the improved device is in all respects the same as in the case of my prior patented collar and tie clasp, previously referred to, and as illustrated in Figure 1, showing the clips 5 attached in gripping relation to the end portions of the collar 10, with the sleeve or guard member 20 positioned underneath and behind the knotted portion 12 of the necktie. In this wearing position, the yielding character of the device accommodates all the pulling strains incident to its use, while at the same time maintaining a firm gripping engagement with the collar and thereby ensuring the holding of the end portions of the collar in their correct position in relation to the necktie.

It will of course be understood that the elements of my improved construction may be made from any appropriate material adapted for devices of this character and which may also be adapted for taking a neat and attractive finish, as is desirable for garment accessories and the like.

Therefore while I have set forth and described a practical and entirely satisfactory form of construction for embodying the stated features of my improvement, I wish to reserve the right to make such modifications as may fall within the scope of the appended claims.

Having thus described my invention, what I claim and desire to secure by Letters Patent is:

1. An elastic or yielding collar holder of the character described comprising; a pair of collar clips each having a shank or stem portion provided with collar gripping means and also formed with laterally extending finger projections, a yielding expansible element connecting said collar clips, and a guard sleeve enclosing said expansible element and the shank portions of said collar clips and also provided with slots for slidably accommodating the finger projections of said collar clips.

2. An elastic or yielding collar holder of the character described comprising, a pair of collar clips each having a shank or stem portion provided with collar gripping means and also formed with laterally extending finger projections, a yielding expansible element having terminals looping over the finger projections of said collar clips, and a guard sleeve enclosing said expansible element and the shank portions of said collar clips and also provided with slots slidably accommodating the finger projections of said collar clips while preventing detachment of the terminals of said expansible element from said finger projections of the collar clips.

3. An elastic or yielding collar holder of the character described comprising, a pair of collar clips each having a shank or stem portion provided with collar gripping means and also formed with laterally extending finger projections, a coil expansion spring connecting said clips and formed with terminal loops for fitting over the finger projections of said collar clips, and a guard sleeve enclosing said expansion spring and the shank portions of said collar clips and also being formed with slots slidably accommodating the finger projections of said clips while preventing detachment of said terminal loops from said finger projections.

4. An elastic or yielding collar holder of the character described comprising, a pair of collar clips each having a shank or stem portion provided with collar gripping means and also formed with laterally extending finger projections, a yielding expansible element having terminals looping over said finger projections of the collar clips, and a split guard sleeve enclosing said expansible element and having mating notches or recesses along its split line adapted to cooperate to provide slots slidably accommodating said finger projections of the collar clips and also preventing detachment of said terminals of the expansible element from said finger projections.

ALBERT C. PATCH.
